UNITED STATES PATENT OFFICE.

BERNARD HANSON, OF MARTIN, OHIO.

HEADLIGHT.

Application filed April 11, 1923. Serial No. 631,277.

To all whom it may concern:

Be it known that I, BERNARD HANSON, a citizen of the United States, and a resident of Martin, Ottawa County, and State of Ohio, have invented a new and useful Headlight, which invention is fully set forth in the following specification.

This invention relates to certain new and useful improvements in headlights and the primary object thereof is to provide improved means for overcoming the objectionable blinding or glaring action of the rays projected by the lights and wherein the light rays will be projected parallel to the horizontal or at an angle below the horizontal.

A further object of the invention is to provide an inclined reflector and novel operating means therefor, by means of which, the light rays projected vertically by the lamp, are intercepted by the reflector and then horizontally projected through the usual vertically disposed lens of the headlights.

Another object of the invention, is to provide a reflector which spreads the light rays laterally so as to effect illumination of the sides of the road and to also provide a reflector of novel form and construction so as to increase the reflecting power thereof.

A further object of the invention is to provide novel and improved means for retaining the lens in position, while still permitting of easy and quick removal and positioning thereof.

Still another object of the invention is to provide novel means for connecting and mutually bracing the two headlights which means serves to house or protect the parts that effect simultaneous operation of each of the two reflectors.

The invention has still further and other objects which will be later set forth and manifested in the course of the following description.

In the drawings:-

Figure 1, is a fragmentary top plan view of an automobile equipped with the present invention;

Figure 2, is an enlarged fragmentary longitudinal sectional view, partly in side elevation of Figure 1;

Figure 3, is an enlarged detail sectional view on line 3—3 of Figure 2;

Figure 4, is a front elevation of the headlight, partly broken away and shown in section;

Figure 5, is a side elevation of Figure 4, parts being broken away and shown in section;

Figure 6, is a section on line 6—6 of Figure 4;

Figure 7, is a section on line 7—7 of Figure 6;

Figure 8, is a section on line 8—8 of Figure 6;

Figure 9, is a section on line 9—9 of Figure 8;

Figure 10, is an enlarged detail view of the clip of the lens lock;

Figure 11, is a section on line 11—11 of Figure 6;

Figure 12, is a section on line 12—12 of Figure 6;

Figure 13, is an enlarged section on line 13—13 of Figure 12;

Figure 14, is an enlarged plan view of the reflector, and

Figure 15, is a section on line 15—15 of Figure 14.

In proceeding in accordance with the present invention, a vertically disposed casing 1 is employed having a parabolic reflector 2 and a light bulb 3 therein. The reflector 2 is held in position by means of bolts 4, which latter also act to hold bar 5 in its position extending diametrically across the upper end of the casing 1. The bar 5 supports semi-circular light intercepting shields or members 6 and 7.

The reflector R is composed of plates 8, 9 and 10, that are each formed with flanges 11 which abut and which are riveted together, as depicted in Figure 15 of the drawings, the outer plate 10, being formed with perforated ears 12 secured by bolts 13 to a bar 14, which latter in turn is secured by bolts 15 to the lens casing 16. The reflector plates are of ovaloid or elliptical form, the central one 8 being curved upwardly toward a line 17 extending axially of the ellipse as indicated in Figures 14, and 15 to spread the rays of light.

The lens casing has a neck 18 and has the front thereof provided with a lens 20, while the rear upper end of the neck thereof is inclined as indicated at 21. The lens 20 is held against the inturned edge 22 of rim or outer ring 23, which latter has pins 24 engaged by curved spring fingers 25, the latter formed on the free edge of the casing 16, the casing 16 having a channel 27, one wall of which has slots 28 to admit the pins. Angle clips

29 are riveted to an inner ring 30 which latter has a channel receiving a circular packing or cushioning ring 31. The clips 29 have corrugated parts 32 which not only hold the fingers 25 in engagement with the pins 24 but also engage in the slots 28 to support the inner ring 30 in position.

For the purpose of effecting any desired inclination of the reflector R, which latter is composed of the parts 8, 9 and 10, the reflector is connected to an arm 33, which has a perforated end slidably receiving a rod 34, the outer end of the rod having adjusting nuts 35 against which the perforated end of the arm 33 is held by a coil spring 36. The inner end of the rod 34 is pivoted between the ends of an arm 37 carried on a rod 38, the rod 38 being turnably mounted in a bracket 39 attached to the lens casing 16. The bracket 39 has a toothed or segmental rack 40 the teeth of which are engaged by a tooth 41 carried by the arm 37. The rod 38 is tensioned by a spring 42 coiled thereabout and abutting a part of the bracket 39. An arm 43 is connected to the rod 38 by screw 43*, and is connected by a rod 44 to an operating or control rod 45, the latter rod having a handle or knob 46 which projects through the instrument board 47. The inner end portion of the rod 45 slides through a bracket 48 that is carried by the frame of the machine. The rod 45 is preferably mounted in a flexible sleeve 49 to prevent rattling.

Referring to Figure 1 of the drawings it will be seen that the brackets 39 are attached to the inner sides of the lens casing 16 adjacent to the upper arcs or ends of the latter, and have projecting shanks 50 to which the ends of an angle plate or bar 51 are secured, the angle bar serving to brace each of the headlight casings and further serving to house a rod 52, which latter corresponds to the rod 38 of the companion headlight, the rods 38 and 52 being connected to the arm 43 so that movement of the latter will effect simultaneous movement of each of the arms 34 and thereby the reflectors in the lens casings of the two headlights. It will be understood, of course, that the above described parts, excepting arm 43 are the same in each of the headlights, the arm 43 being common to each and affording a common operating means accordingly.

In operation, it will be seen that the light rays emanating from the bulb 3 are projected vertically and are intercepted by the shields 6 and 7, so as to intercept the rays of the direct cone of light that would be reflected by the reflector above the horizontal. The light rays being intercepted by the reflector will be reflected through the lens 20 parallel to the horizontal or at an angle below the horizontal, depending upon the inclination 65 of the reflector. The light rays are spread

by the converging curved side portions of the central reflector plate 8, so as to effect illumination of the sides of the road.

In order to effect desired inclination of the reflector R, the rod 45 is slid in the desired direction, thereby effecting corresponding oscillation of the arm 43, the latter operating or turning each of the rods 38 and 52 in unison, and effecting turning of the arms 37 which latter operate the rods 34 and through the arms 33 cause movement of the respective reflectors about their pivotal points 13. The spring 42 serves to hold the tooth 41 of arm 37 in engagement with the teeth of the rack 40, thereby holding the reflectors in any position to which they may be moved. The spring 36 acts to cushion the movement of the reflector in changing the angles of inclination of the latter.

In order to remove the lens from its casing, it is merely necessary to turn the ring 23 to cause the pins 24 thereof to register with the slots 28, whereupon the ring 23 can be moved outwardly, carrying with it the lens 20 and enabling the ring 30 to be then removed.

What is claimed is:—

1. In combination with a pair of headlights each having a casing with a pivoted reflector therein, a bracket carried by each casing and having inner and outer parts which project into and out of the casing, an angle bar connected at its ends to the respective outer parts, a pair of shafts journaled in the brackets and housed by the angle bar, racks carried by the inner parts, the ends of the shafts adjacent to the racks having right-angular arms formed to engage the racks, springs on the shafts to tension same to hold said arms engaged with the racks, means connected to the arms and to the reflectors to actuate the latter, and means common and connected to each of the shafts to actuate same in unison. 100

2. In combination with the casing of a headlight having a pivoted reflector therein, a bracket carried by the casing and extending at one end within the casing, a shaft journaled in the bracket having a right angular arm, a tooth on the arm facing the said end of the bracket, a rack on said end of the bracket engaged with said tooth, a spring surrounding the shaft for tensioning same to hold the tooth engaged with the rack, means on the shaft to rotate same, and means connected to said arm and to the reflector to operate the latter. 110

3. In a headlight, an upwardly facing reflector, a light source, a pivoted reflector above the first named reflector, and means to operate the pivoted reflector including a shaft having a right angular arm provided with a tooth, a rack having its teeth engaged with the tooth of the arm, spring means to tension the shaft to hold the tooth of the 125 130

arm engaged with the rack teeth, a connection between said arm and the pivoted reflector, an operating arm connected to the shaft, and means to actuate the operating arm.

4. In a headlight, an upwardly facing reflector, a light source, a pivoted reflector above the first named reflector, and means to operate the pivoted reflector including a shaft having a right angular arm provided with a tooth, a rack having its teeth engaged with the tooth of the arm, spring means to tension the shaft hold the tooth of the arm engaged with the rack teeth, a rod pivoted to said arm, a spring on the rod, a connection secured at one end to the pivoted reflector and being slideable on the rod and tensioned by said spring, an operating arm connected to the shaft, and means to actuate the operating arm.

5. In combination with a pair of headlights each having a casing with a pivoted reflector therein, a bracket carried by each casing, and having inner and outer parts extending within and without the casing, a connection secured at its ends to the outer parts of the respective brackets, means to operate each reflector including shafts jour-

naled in the brackets and housed by said connection, spring means for tensioning the shafts engaged with the inner parts of the brackets, racks within the casings on the inner parts of the brackets, and teeth on the ends of the shafts engaged with the rack teeth to latch the shafts.

6. In a headlight, a source of light, a main reflector for vertically projecting light rays from said source and a second reflector over the main reflector and including a substantially elliptical member having a flat faced marginal portion to receive and project the outer light rays received from the main reflector in a horizontal beam and having a central portion the opposite sides of which are curved outwardly and meet in a line disposed along the longitudinal axis of the second reflector to divide the central rays received from the main reflector and to spread same laterally to opposite sides of the headlight, the ends of the line of the curved portions terminating at the ends of the central portion.

In testimony whereof I have hereunto subscribed my name to this specification.

BERNARD HANSON.
